[57] CLAIM

The ornamental design for a fastening hook, substantially as shown and described.

DESCRIPTION

FIG. 1 is a left side elevational view of a fastening hook showing my new design;

FIG. 2 is a front elevational view thereof, the rear being a mirror image;

FIG. 3 is a right side elevational view thereof;

FIG. 4 is a top plan view thereof;

FIG. 5 is a bottom plan view thereof;

FIG. 6 is a cross-sectional view taken in the direction of the arrows on line 6—6 of FIG. 2;

FIG. 7 is a cross-sectional view taken in the direction of the arrows on line 7—7 of FIG. 2;

FIG. 8 is a cross-sectional view taken in the direction of the arrows on line 8—8 of FIG. 2;

FIG. 9 is a reduced front elevational view thereof, the portion of a strap being shown in broken lines for illustrative purposes only.

FIG. 1

FIG. 2

FIG. 3

FIG. 4

FIG. 5

FIG. 6

FIG. 9

FIG. 7

FIG. 8
